UNITED STATES PATENT OFFICE.

ARNOLD W. ZIMMERMAN, OF CHICAGO, ILLINOIS.

FOLDING TABLE.

Application filed September 14, 1925. Serial No. 56,172.

This invention relates generally to tables and is particularly concerned with a table of folding construction which is adapted to be readily set up and collapsed.

5 One of the principal objects of the invention is the provision of a table suitable either for continuous or infrequent service, one which may be compactly folded to occupy a minimum of space when not in use 10 and which will provide seating accommodations for a large number without interference or inconvenience from the supporting members.

Another object of the invention is the provision of a folding table of simplified construction adapted for connecting in series with other tables, with a leaf or spacing connection therebetween for eliminating superfluous supporting legs or elements.

20 A further object is the provision of novel and improved means for holding the supporting members securely in both their open and closed positions.

The invention provides an easily manipulated folding table of light, strong, durable and firm construction, which is highly efficient but inexpensive, and possesses numerous advantages other than those specifically set forth, as will be apparent from the drawings, understood when the specification is 30 read and pointed out in the appended claims.

I have shown in the accompanying drawings only what I consider to be a preferred embodiment of the invention, but by stating this preference it is to be understood that I do not intend to suggest any limitation in the application of the invention. The drawing is for illustration purposes only, and should not react to curtail unnecessarily the 40 scope of the claims, as obviously various modifications of incidental details of the invention will occur to others and may be employed with satisfactory results.

In the drawing:

45 Fig. 1 is a perspective view of a table embodying the invention;

Fig. 2 is a vertical section through line 2—2 of Fig. 1;

Fig. 3 is a bottom plan view of the table 50 when folded;

Fig. 4 is a fragmentary detail view of the supporting brace and the catch therefor; and

Fig. 5 is an enlarged cross sectional view 55 on line 5—5 of Fig. 1 showing the interlocking arrangement of the table with a spacing

member or leaf for use when several units are connected in series.

The top 10 of the table has associated therewith, after the usual manner, an apron 60 11. The sides of the apron 11 are drilled near their ends to provide openings 12 to receive the legs 13 of the supporting frame. The supporting frame, as shown, is substantially U-shaped, and is formed from ordinary $\frac{1}{4}$ 65 inch galvanized pipe or tubing. The upper ends of the legs 13 may be bent outward to pass through the openings 12 and provide a pivotal connection for the supporting frame, but I prefer to employ the more simple expedient of inserting in the openings 12, one of the ends of the transverse member of an ordinary T 13^a and to connect thereto the end of the leg 13 by screw threaded engagement with the stem of the T. The bottom 70 75 or floor portion 14 of the supporting frame is bowed slightly upward toward the center so that the outer ends thereof rest upon the floor when the table is set up. The floor portion tends to distribute the weight of the 80 table and its contents over a wide area, and will be found effective in eliminating the usual rocking due to uneven floors.

Strength and rigidity may be added to the supporting frame by tensioning heavy wires 85 13^b between the upper ends of the legs and the center of the floor portion.

A brace or supporting member 15 is rotatably attached by a T 15^a to the medial portion of the floor member 14 and is provided 90 at its free end with a bent catch engaging portion 16 which is adapted to be retained by the catch member shown in Fig. 4, when the table is set up. Said catch member comprises an iron strap 17 which is fixedly secured to the under side of the table top 10 by means of screws 18 and which has its ends bent away from the table to form a right-angled retaining portion 19 and a spring portion 21. The perpendicular portion 19 of the strap is provided with an opening 20 to receive the engaging portion 16 of the bracing member 15. The spring portion 21 is adapted to bear against the bracing member 15 and retain the engaging 95 portion 16 within the opening 20. The bracing member thus provides a rigid support for maintaining the legs in upright position.

A right-angled finger 22 extends from the 110 base portion of the strip 17 and is adapted to be turned to bridge the opening defined by

the three sides of the strap, and to hold the brace member 15 therein when the table is collapsed.

The table is set up by placing the legs in 5 perpendicular relationship to the top and snapping the engaging portion 16 of the brace or supporting rod 15 into the opening 20 of the catch member 17.

To fold or collapse the table the spring 21 10 is depressed and the supporting member 15 removed from engagement with the catch member 17. The legs are then swung inwardly toward the center of the table and the free end of the bracing member is swung 15 outwardly toward the end of the table, until both rest against the top as shown in Fig. 3. In this position the bracing member lies across the strap 17 within the confines thereof and is therein retained by turning of the 20 finger 22. The complete supporting structure is retained in place within the apron of the table and several tables when collapsed may be piled one upon another, or a single table can be conveniently stored in a small 25 space.

The supporting members may advantageously be constructed of pipe lengths joined at the corners by elbows and utilizing tees for connecting the bracing members as shown 30 in the drawing. Or, the complete structure may be made of tubing or solid stock which may be bent to form the component parts.

Two or more tables may be coupled to 35 provide extraordinary seating accommodations by interposing leaves, such as the leaf 27, between the ends thereof; thereby making the supporting structure perform double duty.

To facilitate this arrangement the ends of 40 the table are provided with a plurality of socket members 28 which are adapted to receive the catch members 29, oppositely disposed on the ends of the leaf 27.

Each socket 28 comprises a recess 30 in 45 the edge of the table, covered by a slotted angular metallic piece 31 which fits over the edge of the table and rests upon a marginal

ledge 32 which is countersunk into the top of the table about the sides of the recess. The piece 31 is fastened by means of bolts 50 or screws 31^a. Each catch member 29 is composed of a metal strap secured at one end to the leaf 27 and bent at right angles at the other end to form a hook which is adapted to be inserted and held within the 55 slot of a socket 28.

I claim:

1. In a folding table, the combination of a top, latch means on the under side of said top, a plurality of table legs pivoted to said top and connected in pairs at the bottom thereof by bowed base members, a rigid brace rod attached to each of said base members, said latch means comprising metallic straps, each of said straps having one end 60 bent and apertured and receiving the free end of one of the brace members and having the other end bent to form a spring adapted to engage said brace member to hold it in engagement with the first-mentioned end when 65 the legs are in table-supporting position.

2. In a folding table, the combination of a top, an apron, latch means on the under side of said top, a plurality of table legs pivoted to said apron and connected in pairs 70 at the bottom thereof by bowed base members, T's secured to the upper end of said legs and adapted to fit into holes provided in said apron, a rigid brace rod attached to each of said base members, said latch means 75 comprising metallic straps, each of said straps having one end bent and apertured and receiving the free end of one of the brace members and having the other end bent to form a spring adapted to engage said brace 80 member to hold it in engagement with the first-mentioned end when the legs are in table-supporting position, and a finger attached to each of said straps and adapted to be turned to bridge the space between the 85 ends of said strap.

In testimony whereof I have hereunto subscribed my name.

ARNOLD W. ZIMMERMAN.
